UNITED STATES PATENT OFFICE

2,586,059

COPYHOLDER PAPER SUPPORT

Charles H. Koeppl, North Woodbury, Conn., assignor, by mesne assignments, to Rite Line Corporation, Washington, D. C., a corporation of Delaware

Application October 2, 1950, Serial No. 187,965

2 Claims. (Cl. 120—29)

1

The present invention relates to an attachment for a copyholder and is especially adapted for use with copyholders of the type disclosed in Patents No. 1,939,671, No. 2,162,706, and No. 2,273,841.

Through use of copyholders of the type above mentioned, it has been found that, due to the flimsy nature of paper, the copy tends to follow the contour of the copyholder casing in back of the eye guide and then drop behind the copyholder, with the result that the copying thereof is rendered more difficult by the slant at which the print must be read. Another disadvantage stemming from the above is the casting of a shadow on the line being copied by the eye guide, a consequence of the copy not being flush against the eye guide.

It is therefore the principal object of the present invention to provide a paper guide for a copyholder which supports the copy above the copyholder in such a manner as to permit more facile reading thereof and to eliminate shadows.

Another object of the present invention is to provide a paper guide which is laterally extensible to accommodate paper of varying width.

Other objects of the invention will be evident from the following detailed description read in connection with the appended drawings wherein:

Figure 1 is a perspective view of the paper guide of the present invention attached to a copyholder.

Figure 2 is a side elevational view of the same.

Figure 3 is a rear elevational view of the paper guide per se showing in phantom lines the frame in extended position.

Figure 4 is a rear elevational view of the guide flap forming a part of the present invention.

Figure 5 is a rear elevational view of one of the frame sections forming a part of the present invention.

Figure 6 is a fragmentary vertical sectional view taken along the line 6—6 of Figure 3.

Figure 7 is a vertical sectional-elevational view taken along the line 7—7 of Figure 3.

Figure 8 is a vertical sectional view taken along the line 8—8 of Figure 4.

Figure 9 is a vertical sectional view taken along the line 9—9 of Figure 5.

Figure 10 is a plan view of the blank from which the sleeve forming a part of the present invention is formed.

Referring now in greater detail to the drawings, in Figures 1 and 2 I have shown the device of the present invention attached to a copyholder which comprises generally a casing 11, a tubular paper retainer 12, paper feed rings 13, a spacer

bar 14 and a spring actuated paper presser and eye guide 15. To presser and eye guide 15 is attached the paper guide forming the present invention and embodying a guide flap 16 and an extensible frame 17.

Referring now to Figures 4 and 8, guide flap 16 consists of a single sheet of metal bent to form a channel 18, the purpose of which will be hereinafter more fully described. The rear section 19 of guide flap 16 is struck out at intervals as indicated at 20 to form supports 21. The front portion 22 of guide flap 16 is considerably longer than the rear, the extended section being curvilinear to complement the contour of similar shaped pressers and eye guides. Adjacent the lower edge of front portion 22 the metal is pressed out to form projections 23 which snap over the upper part of presser and eye guide 15 to hold the paper guide in place.

Extensible frame 17 comprises a pair of U-shaped sections 24 (see Figures 5 and 9). These sections of the frame member are placed with the free ends of their longitudinal rods overlapping and the free terminal of each top rail has riveted to it at 25 a sleeve 26 (see Figure 7).

Each sleeve is preferably formed from the blank shown in Figure 10, and is bent over the overlapping rail to hold the lapped and overlapped portions of the mentioned rails in contiguous relation but permitting relative sliding movement of the sections. Sleeves 26, when abutting, also serve to limit the amount of lateral extension of the frame sections. The lower rail of each frame section 24 is trained in channel 18 of guide flap 16 and rests on supports 21. To frictionally retain frame 17 in association with guide flap 16, the opposite ends of channel 18 are contracted by having the lower lateral extremities of rear portion 19 of flap 16 pinched as indicated at 27 (see Figures 3 and 6).

In use, frame 17 of the paper guide is longitudinally adjusted to the paper width by manually manipulating frame sections 24 in an obvious manner. The copy is then placed in tubular retainer 12 and passed upwardly between feed rings 13 and presser 15 by operation of spacer bar 14. The back of the copy rests against the top member of the paper guide so that the paper remains in an easily readable condition from the eye guide 15 to the top member of the frame and lies flush against presser and eye guide 15 to eliminate shadows.

Although I have herein shown a preferred form of the invention, I am nevertheless aware that

various changes may be made therein within the scope of the claims hereto appended.

What I claim is:

1. A paper guide attachment for a copyholder comprising a plurality of frame sections in overlapped relation, sleeves for keeping the top rails of said frame sections contiguous and in sliding relation to each other, a guide flap adapted for attachment to the copyholder, and said guide flap having a channel for slidably accommodating the lower rails of said frame sections.

2. Same as claim 1 wherein the guide flap is

struck out at intervals to form supports for the frames.

CHARLES H. KOEPPEL.
